TOY ROCKET CHUTE

William E. Dodds, Corsicana, Tex.

Application March 6, 1944, Serial No. 525,209

1 Claim. (Cl. 46—86)

This invention relates to a toy, the primary object of the invention being to provide a toy in the form of an arrow or rocket, having a compartment at its feather end, and in which an article such as a parachute or the like may be folded and retained, to be automatically released when the arrow or rocket is shot into the air, reaches a predetermined height, whereby the parachute or article may drift to the ground surface, providing a toy which is exceptionally attractive and amusing.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Referring to the drawing,

Figure 1 is an elevational view of a rocket or arrow, constructed in accordance with the invention, illustrating the cover of the compartment thereof, as open to release the parachute folded therein.

Figure 2 is a view illustrating the pointed end of the arrow, and the parachute as floating to the earth.

Figure 3 is an elevational view of the arrow or rocket, the closure for the compartment thereof being closed, the sling or projecting device used with the arrow or rocket, being shown as connected therewith.

Figure 4 is an edge elevational view of the arrow, illustrating the closure of the compartment as closed.

Figure 5 is a view illustrating a parachute as connected with the arrow or rocket, to open and retard downward movement of the arrow or rocket.

Referring to the drawing in detail, the arrow comprises a body portion which is in the form of a stick indicated at 5, the forward end thereof being pointed, at 6. The opposite end of the body 5 is enlarged and is substantially circular in formation, the enlarged end of the body 5 being hollowed out, providing a compartment 7 in which a parachute 8 is folded, to be released when the arrow or rocket reaches a predetermined height, during its projection through the air.

The compartment is closed by means of a pivoted closure 9 which closure is formed with an extension 10 adapted to overlie the extension 11 of the enlarged portion of the arrow, when the closure is in its closed position.

An elastic member 12 connects the body 5, with

the closure 9, so that under normal conditions, the closure is moved to its open position, as shown by Fig. 1 of the drawing. When the closure 9 is in its closed position, and the extension 10 there-
5 of overlies the extension 11, the closure is held in its closed position, by means of the cord 13 which is secured to the extension 11, and is wound around the extensions 10 and 11, as shown by Fig. 3, securing the closure against moving to its open position, under normal conditions. A weight indicated at 14 is secured to the free end of the cord 13 to pull the free end of the cord downwardly, during the flight of the arrow, thereby unwinding the cord 13 and releasing the closure,
10 which in turn releases the parachute folded there-
15 in. In Fig. 5 of the drawing, the shroud lines 15 of a parachute, are shown as connected to one end of the extension 11 of the arrow, so that when the parachute is released, the parachute
20 will open and act to retard the descent of the arrow.

The sling or projecting device by means of which the arrow or rocket is shot into the air, includes a handle 16 to which an elastic member
25 17 is connected, the opposite end of the elastic member being supplied with a cord 18 having a knot 19 at its free end.

A slot indicated at 20 extends inwardly at an oblique angle with respect to the side of the body
30 5, at a point in proximity to the pointed end of the body 5. By placing the cord in the slot and holding the handle 16 with one hand, while pulling the arrow rearwardly stretching the elastic member 17, the arrow or rocket will be shot into
35 the air when released. During the ascent of the arrow, the weight 14 will cause the cord 13 to unwind, releasing the closure 9, whereupon the parachute will fall from its compartment and unfold, whereupon the descent of the parachute
40 will be retarded.

What is claimed is:

A toy comprising an arrow having an enlarged substantially flat feather end portion, said enlarged end portion being recessed providing a
45 compartment, a closure for the compartment, said compartment adapted to contain a folded para-
chute, an extension disposed rearwardly upon the wall of the compartment, an extension on the closure adapted to overlie the extension on
50 the compartment, a cord wrapped around the alining extensions, a weight on one end of the cord adapted to unwind the cord releasing the closure, an elastic member connected with the closure and arrow and adapted to normally pull
55 the closure open, when the cord becomes un-
wrapped.

WILLIAM E. DODDS.
